UNITED STATES PATENT OFFICE.

JOHN A. SECOR, OF LAPORTE, INDIANA, ASSIGNOR TO ADVANCE-RUMELY COMPANY, OF LAPORTE, INDIANA, A CORPORATION OF INDIANA.

REATOMIZER.

Original application filed June 30, 1919, Serial No. 307,682. Patent No. 1,480,959, dated January 15, 1924. Divided and this application filed December 21, 1922. Serial No. 608,231.

To all whom it may concern:

Be it known that I, JOHN A. SECOR, a citizen of the United States, residing at La-
porte, in the county of La Porte and State
of Indiana, have invented a certain new and
useful Improvement in Reatomizers, of
which the following is a specification.

My invention relates to improvements in
fuel mixing and particularly has reference
10 to a reatomizing device whereby fuel which
has been mixed with air is remixed or re-
atomized upon its introduction into the cyl-
inder in which it is to be used. This ap-
plication is a division of my co-pending
15 application Serial Number 307,682, filed
June 30, 1919.

It is, of course, well-known that when
liquid fuel is aspirated by a rapidly moving
current of air, the sudden change in ve-
20 locity of the liquid and the sudden change
in the pressure to which it is subjected
among other forces, results in more or less
communizing or atomizing the liquid so that
it readily mixes with the air to form a com-
25 bustible fluid.

Experience shows, however, that particu-
larly with heavier fuels, such as kerosene
and the heavier fractions or distillates, you
are likely to have difficulty in that the fuel
30 which is caught up by the air may be re-
deposited along the walls and passages
through which it travels and particularly
is this the case after the combustible mix-
ture has passed by a throttle valve, the
35 throttle valve tending to change the direc-
tion of flow, and to separate out the fuel so
that you may even get an actual stream of
liquid running down the walls of the pas-
sage, which stream of liquid has been taken
40 out of a satisfactory mixture by the mere
presence of the partially closed throttle
valve.

This difficulty is also present when you
are using water as a part of the combustible
45 mixture, and it is, of course, quite undesir-
able that this liquid fuel or liquid water be
allowed to get into the cylinder in anything
but a gaseous or finely divided condition,
both because either the liquid fuel or liquid
50 water hinders the combustion and because
liquid ingredients in the cylinder are likely
to cause dilution of the lubricant in the
crank case.

My invention therefore takes the form of
a device or devices which have for their pur-
pose to reatomize the combustible liquid, or
water and mix or assist in the mixing of it
with the air.

My invention is more or less diagrammati-
cally illustrated in the accompanying draw-
ings, wherein:

Figure 1 is a vertical cross section
through a cylinder wall showing the inlet
valve, a portion of the inlet manifold, and
the reatomizing device;

Figure 2 is a vertical cross section on a
reduced scale showing the device in posi-
tion in the top of the cylinder.

Like parts are designated by like char-
acters throughout.

A is a part of the engine cylinder casting,
which as here shown includes an inlet pas-
sage A¹. Seated within the end of this pas-
sage and communicating with the cylinder
is an inlet valve B mounted on the valve
stem B¹. B² is a bevelled valve seat in
which the valve B is seated to close it. B³
is the reatomizing member. It is formed
here integral with the valve seat, although
its construction might be varied. B⁴ is a
closed trough formed in the member B, open
toward the upstream side, that is in the di-
rection of the incoming fuel. As here shown
it is preferably provided with a sharp inner
edge.

C is a fragment of the engine cylinder
casting which may be of any suitable form
and is here provided with an inlet passage
C¹. D is an inlet valve carried by a valve
stem D¹. D² is a bevelled seat in which the
valve is seated when closed. D³ is the re-
atomizing device and is provided with a
trough D⁴ which is open only toward the
incoming fuel and is preferably provided
as here shown with a sharp inner edge.

Although I have shown an operative de-
vice, still it will be obvious that many
changes in size, shape and arrangement of
parts might be made without departing ma-
terially from the spirit of my invention; and
I wish therefore that my showing be taken
as in a sense diagrammatic. Particularly
the valve might be seated independent of
the reatomizing device, and the valve seat
and the reatomizing device would in that
case be separate members.

2
The use and operation of my invention are as follows:

In practically all types of engines in which the fuel is mixed with air before being introduced into the engine cylinder, this mixing takes place at a point somewhat separated from the actual point of introduction of the fuel into the cylinder where it is to be burned. The mixed fuel is then conducted to the engine cylinder through an inlet manifold or passage of any suitable sort. During its movement from the point of mixing to the engine cylinder some of the fuel may be deposited out of the air current in the form of drops. This is particularly likely to occur where the fuel is comparatively non-volatile, but it does occur in the case of almost every fuel. When such fuel is deposited out of the air current, it is in the form of drops which form upon the walls of the inlet passage. Such drops will be carried toward the inlet opening by means of the air current and in usual constructions will frequently be carried into the combustion chamber in liquid form. This introduction of liquid fuel into the cylinder results in unsatisfactory and unequal burning and is to be avoided.

In the construction shown there is provided about the inlet opening and closed to it a trough, open on one side toward the incoming stream of fuel, and closed elsewhere. The drops of fuel which have been deposited on the walls of the inlet chamber and passage are gradually carried down and into this trough and as they accumulate, they fill the trough and overflow the edges of the trough. As the fuel overflows the edges of the trough, which are preferably sharp, it is seized by the air current and is broken up and again atomized, and so in its re-atomized form joins the mixed fuel stream and is carried into the engine cylinder in satisfactory condition for burning.

45 I claim:

1. In an internal combustion engine, a cylinder, an inlet pipe, an inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder.

2. In an internal combustion engine, a cylinder having a combustion chamber, a pipe providing an inlet passage leading into said chamber, an inlet valve and seat between said combustion chamber and said passage, means adjacent to said inlet valve seat for collecting solid liquid fuel accumulating on the walls within said passage and for converting the same into a mist directly at the entrance to said combustion chamber.

3. In an internal combustion engine, a cylinder, an inlet pipe, an inlet valve and

valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising an annular trough opening in the direction of the incoming fuel stream.

4. In an internal combustion engine, a cylinder having a combustion chamber, a pipe providing an inlet passage leading into said chamber, an inlet valve and seat between said combustion chamber and said passage, means adjacent to said inlet valve seat for collecting solid liquid fuel accumulating on the walls within said passage and for converting the same into a mist directly at the entrance to said combustion chamber, said means comprising an annular trough opening in the direction of the incoming fuel stream.

5. In an internal combustion engine, a cylinder, an inlet pipe, an inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising an annular trough opening in the direction of the incoming fuel stream and closed elsewhere.

6. In an internal combustion engine, a cylinder having a combustion chamber, a pipe providing an inlet passage leading into said chamber, an inlet valve and seat between said combustion chamber and said passage, means adjacent to said inlet valve for collecting solid liquid fuel accumulating on the walls within said passage and for converting the same into a mist directly at the entrance to said combustion chamber, said means comprising an annular trough opening in the direction of the incoming fuel stream and closed elsewhere.

7. In an internal combustion engine, a cylinder, an inlet pipe, an inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising an annular trough opening in the direction of the incoming fuel stream and closed elsewhere, said trough provided on its inner side with a sharp edge.

8. In an internal combustion engine, a cylinder having a combustion chamber, a pipe providing an inlet passage leading into said chamber, an inlet valve and seat between said combustion chamber and said passage, means adjacent to said inlet valve for collecting solid liquid fuel accumulating on the

- walls within said passage and for converting the same into a mist directly at the entrance to said combustion chamber, said means comprising an annular trough opening in the direction of the incoming fuel stream and closed elsewhere, said trough provided on its inner side with a sharp edge.
9. In an internal combustion engine, a cylinder, an inlet pipe, an inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising a Venturi tube having an annular channel in the interior wall thereof, said channel being open only to the interior of said inlet pipe, and situated at the smallest diameter of the venturi.
10. In an internal combustion engine, a cylinder having a combustion chamber, a pipe providing an inlet passage leading into said chamber, an inlet valve and seat between said combustion chamber and said passage, means adjacent to said inlet valve seat for collecting solid liquid fuel accumulating on the walls within said passage and for converting the same into a mist directly at the entrance to said combustion chamber, said means comprising a Venturi tube having an annular channel in the interior wall thereof, said channel being open only to the interior of said inlet pipe, and situated at the smallest diameter of the venturi.
11. In an internal combustion engine, a cylinder, an inlet pipe, an inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising a Venturi tube having an annular channel in the interior wall thereof, said channel being open only to the interior of said inlet pipe, and situated at the smallest diameter of the venturi, the channel being bounded on its exposed side by a sharp edge.
12. In an internal combustion engine, a cylinder having a combustion chamber, a pipe providing an inlet passage leading into said chamber, an inlet valve and seat between said combustion chamber and said passage, means adjacent to said inlet valve seat for collecting solid liquid fuel accumulating on the walls within said passage and for converting the same into a mist directly at the entrance to said combustion chamber, said means comprising a Venturi tube having an annular channel in the interior wall thereof, said channel being open only to the interior of said inlet pipe, and situated at the smallest diameter of the venturi, the channel being bounded on its exposed side by a sharp edge.
13. In an internal combustion engine, a cylinder, an inlet pipe, and inlet valve and valve seat at the end of said pipe where it enters the cylinder, means adjacent to the inlet valve seat to collect solid liquid fuel accumulating on the internal walls of said pipe, and to convert the same into a mist directly at the entrance to said cylinder, said means comprising a portion of said inlet pipe of reduced diameter and having situated therein a channel in the interior wall thereof, said channel being open only to the interior of said inlet pipe.
14. In an internal combustion engine, a cylinder having a combustion chamber, a pipe providing an inlet passage leading into said chamber, an inlet valve and seat between said combustion chamber and said passage, means adjacent to said inlet valve seat for collecting solid liquid fuel accumulating on the walls within said passage and for converting the same into a mist directly at the entrance to said combustion chamber, said means comprising a portion of said inlet pipe of reduced diameter and having situated therein a channel in the interior wall thereof, said channel being open only to the interior of said inlet pipe.
- Signed at Laporte, county of La Porte, and State of Indiana, this eighteenth day of December, 1922.

JOHN A. SECOR.
